HUB CAP

Application filed August 16, 1929. Serial No. 386,257.

This invention relates to certain improvements in hub caps or the like for use with motor car wheels of that type in which the cap can be readily snapped into position on the 5 hub of the wheel and readily removed therefrom.

These hub caps are used for closing in the open end of wheels, particularly wheels used with motor cars in which the means for securing 10 the wheel in position are located inside the hub of the wheel, which necessitates the removal and replacement of the cap. It is desirable with this type of hub cap that the parts may be quickly assembled and read- 15 ily removed and replaced on the hubs when it is desired to remove a wheel, or for other purposes. It is further desirable that these constructions be cheap and the parts so correlated that they may be readily removed and 20 placed in position, but at the same time remain in place during the operation of the vehicle with which they are used. In a co-pending application of Frederick R. Reutter, Serial No. 325,736, filed December 13, 25 1928, is shown and described a construction in which certain resilient means are employed for holding the cap in place on the hub and yet permitting its ready removal and replacement when necessary.

It is the especial object of the present invention to provide an improved and simplified means for thus holding the cap in place.

It is a further object of the invention to provide a cap for these resilient holding 35 means which shall be of few parts, with the parts so arranged as to permit a quick assembly, and which shall be strong and durable.

With these and other objects not specifically referred to in view, the invention consists in certain novel parts, arrangements and combinations which will be described in connection with the accompanying drawings and the novel features pointed out in the claims 45 hereunto annexed.

In these drawings,—

Figure 1 is an inner face view of a hub cap embodying the features of the invention, and

Figure 2 is a sectional view taken on the

line 2—2 of Figure 1, showing the outer end of the hub in section with the cap fitted thereto.

Referring now to these drawings, the hub cap which has been selected to illustrate the 55 invention comprises a two part structure including an outer plate 1 and an inner plate 2. This construction permits the use of a thin metal for the outer plate, which can be externally decorated as desired, and an inner 60 plate of a relatively stronger metal, which provides the necessary strength and rigidity for the cap. It will be understood, however, that under certain circumstances and where desired the outer plate may be omitted, the 65 inner plate only being used as the main body of the cap. Where, however, two plates are used, as in the construction shown, these two plates are secured together, and this may be conveniently effected by turning in the outer 70 edge of the outer plate over the outer edge of the inner plate, as indicated at 3 in Figure 2, though, of course, if desired, these plates may be secured together in other ways, as, 75 for instance, by spot welding. The construction shown, however, provides in effect a bead which spaces the cap slightly away from the hub, so that it can be readily removed by the insertion of a suitable tool between the cap and the hub. This plate is capacitated 80 to be secured to a wheel hub, indicated at 4, this hub being provided with an inturned flange 5, which surrounds a central opening 6, 85 the wheel and the means for securing the wheel in position being omitted, as unnecessary for an understanding of the invention.

The hub cap, whether in one or two parts, will include certain resilient holding devices by which the cap may be removably secured to the hub. In order to save metal and thus cheapen the construction, the holding devices of the present invention will include spaced supports which act as carriers for the resilient means employed. While the number of these supports may vary, in the particular construction illustrated the inner 90 plate 2 has secured thereto a pair of oppositely disposed substantially L-shaped brackets 7, 8, the radial legs of which are arranged to 95 extend inwardly and are secured to the inner 100

plate in any suitable manner, as by rivets 9. The axially extending legs 10 of these brackets are of a diameter substantially that of the opening 6 in the wheel hub, and secured to the axial legs 10 of these brackets are resilient holding devices which may be somewhat varied in construction. In the particular construction illustrated, in order to provide an effective holding grip of the cap on the hub, each of these brackets will carry a holding device which will engage the hub at two points spaced apart, thus saving in material and at the same time providing an effective securing means. While the particular construction of the holding devices adopted to effect this may be somewhat varied, in the particular construction illustrated each bracket is provided with a strip of spring metal 11, suitably secured to the brackets, as by rivets 12, this strip extending beyond the brackets at each side and being provided at each side with a holding projection, these holding projections being shown in the form of pins 13, 14, preferably made of hard metal, and secured to the strip 11 in any suitable manner, as by rivets 15.

These holding projections, when in their normal position, are of a greater diameter than the opening 6 in the hub, and when the cap is forced onto the hub the spring of the strip 11 permits the holding projections to yield until after they have passed the edge of the flange 5, when the spring of the metal permits them to snap behind the flange and securely lock the cap in place on the hub. Thus a simple and economical arrangement has been provided which can be cheaply made and assembled, and which will securely hold the cap in place but permit its ready removal without injury thereto.

While the invention has been shown and described in a preferred form, it will be understood that certain variations will be permissible in the form and arrangement of the holding devices and in the way they are supported in the cap without departing from the invention as defined in the appended claims.

What I claim is:

50 1. An automobile hub cap assembly comprising a metal hub open at one end and having a continuous inwardly extending radial peripheral flange surrounding the opening, a hub cap arranged to be secured on the hub 55 in any circumferential position by a straight line movement, said hub cap including a metal plate, the inner face of this cap being provided with spaced brackets, one leg of each bracket being secured to the inner face 60 of the plate and the other leg of each bracket extending inwardly, said inwardly extending bracket legs being substantially the diameter of the opening in the hub, spring strips secured to each bracket, and nibs secured at 65 each end of each strip arranged to snap be-

hind and engage the rear face of the hub flange when the cap is associated with the hub and acting to hold the cap securely in place on the hub.

2. An automobile hub cap assembly comprising a metal hub open at one end and having a continuous inwardly extending radial peripheral flange surrounding the opening, a hub cap arranged to be secured on the hub in any circumferential position by a straight line movement, said hub cap including a metal plate, the inner face of this cap being provided with spaced brackets, one leg of each bracket being secured to the inner face of the plate and the other leg of each bracket extending inwardly, said inwardly extending bracket legs being substantially the diameter of the opening in the hub, a strip of spring metal secured to each bracket intermediate its ends, and hard metal nibs secured to the free ends of the strips and arranged to snap behind and engage the rear face of the hub flange when the cap is associated with the hub and acting to hold the cap securely in place on the hub.

In testimony whereof, I have hereunto set my hand.

JOSEPH R. WOLFF.
